US0D1042796S

(12) **United States Design Patent** (10) **Patent No.:** **US D1,042,796 S**
(45) **Date of Patent:** **** Sep. 17, 2024**

(54) **MEDICATION CARTRIDGE**

(71) Applicant: **Aspargo Laboratories, Inc.**, New York, NY (US)

(72) Inventors: **Adam Demurjian**, Red Bank, NJ (US); **Josh Probst**, Thousand Oaks, CA (US); **Lance Hussey**, Thousand Oaks, CA (US); **Ravi Sawhney**, Thousand Oaks, CA (US)

(73) Assignee: **ASPARGO LABORATORIES, INC.**, New York, NY (US)

(**) Term: **15 Years**

(21) Appl. No.: **29/930,643**

(22) Filed: **Mar. 1, 2024**

(51) LOC (14) Cl. **29-02**

(52) U.S. Cl. **USPC D24/110**

(58) **Field of Classification Search**

USPC ..... D24/107, 108, 109, 110, 111, 113, 115, D24/118, 127, 164, 165, 182, 207; D9/500, 502, 557, 568, 569, 685-688; D27/164 CPC .. A61M 2210/0618; A61M 2210/0625; A61M 16/00; A61M 16/0003; A61M 2206/07; A61M 2206/071; A61M 2206/8206; A61M 1/00; A61M 1/60; A61M 1/71; A61M 1/76

(57) **CLAIM**

The ornamental design for a medication cartridge, as shown and described.

DESCRIPTION

FIG. 1 is a top, isometric-view of a medication cartridge; FIG. 2 is a bottom, isometric-view of the medication cartridge;

FIG. 3 is a front-view of the medication cartridge;

FIG. 4 is a rear-view of the medication cartridge;

FIG. 5 is a right, side-view of the medication cartridge;

FIG. 6 is a left, side-view of the medication cartridge;

FIG. 7 is a top-view of the medication cartridge; and,

FIG. 8 is a bottom-view of the medication cartridge.

The broken lines in FIGS. 1, 2, 3, and 8 illustrate portions of the medication cartridge that form no part of the claimed design.

1 Claim, 7 Drawing Sheets
